UNITED STATES PATENT OFFICE.

CHARLES C. BULL, OF LESTER, IOWA.

WRENCH.

No. 826,401.

Specification of Letters Patent.

Patented July 17, 1906.

Application filed September 14, 1905. Serial No. 278,437.

To all whom it may concern:

Be it known that I, CHARLES C. BULL, a citizen of the United States, residing at Lester, in the county of Lyon and State of Iowa, have invented a new and useful Improvement in Wrenches, of which the following is a specification.

My invention relates to certain new and useful improvements in wrenches, and has for its object to provide a wrench which is very simple and cheap in construction and one that can be quickly adjusted with one hand with the greatest of ease.

Another object of my invention is to provide a wrench that is so constructed that it can be used in close quarters with great advantage over other wrenches.

A further object of my invention is to provide a screw-driver in connection with one of the jaws of the wrench inclosed in a handle, so that when the jaws are closed the screw-driver will project out of the end of the handle so that it can be used.

With these objects in view my invention consists of the novel construction and arrangement of parts hereinafter fully described, pointed out in the claims, and shown in the accompanying drawings, in which—

Figure 1 is a perspective view of the wrench. Fig. 2 is a sectional view of the wrench, showing the jaws closed. Fig. 3 is a sectional view of the wrench, showing the jaws opened. Fig. 4 is a section taken on line 4-4 of Fig. 2. Fig. 5 is a section taken on line 5-5 of Fig. 2.

Referring to the drawings, A indicates the hollow handle, which is provided with the flattened portion A', which tapers outwardly, forming a socket for the jaws and is provided with recesses on its inner sides adjacent its end, in which are secured by screws A² serrated blocks A³. A slot A⁴ is formed in the flattened portion A' adjacent the handle, through which the adjusting-ring B is adapted to be connected to one of the jaws.

Arranged in the socket are jaws C and D, the inner side of the jaw D being serrated, and the jaws are provided with the usual heads C' and D', having serrated edges C² and D², adapted to engage the block secured in the side of the socket and securely lock the jaw in the position desired. The jaws are provided with grooves C³ and D³, formed in

the sides in which the lugs A⁵ and A⁶ of the socket are adapted to work. The jaw C is the longest of the two and is provided with a screw-driver C⁴, formed on its end adapted to extend out through the opening A⁷ in the end of the handle when the jaws are closed. A reduced portion is found midway the length of the jaw C, on which the jaw D, which is provided with a reduced portion to correspond, is pivoted by the pin C⁵. The jaw D is connected to the ring B by the screw B', which holds the jaw in place. A reduced portion is formed on the edge of each jaw, in which are secured the flat springs C⁶ and D⁴, which have the tendency to throw the jaws apart, so that they will always be open, allowing the jaws to be quickly adjusted to suit the size of nut desired by shoving the ring back and forth.

Having thus fully described my invention, what I claim as new, and desire to secure by Letters Patent, is—

1. In a wrench of the kind described, the combination with a handle provided with a tapering socket provided with detachable serrated blocks of a pair of jaws pivoted together adapted to slide back and forth in said socket springs arranged in said socket, adapted to throw the pivoted jaws against the serrated block and a ring surrounding said handle connected to one of the jaws for moving said jaws, for the purpose described.

2. In a wrench of the kind described, the combination with a hollow handle provided with a tapering socket having serrated edges, of a pair of jaws pivoted together provided with serrated edges, arranged in said socket, springs arranged on each side of the jaws in the socket, adapted to throw the serrated edges of the jaws in engagement with the serrated edges of the handle one end of one of said jaws extending out through one end of the handle and means for adjusting the jaws in said socket for the purpose described.

3. In a wrench of the kind described the combination with a hollow handle provided with a tapering socket provided with detachable, serrated blocks adjacent its outer end, of a pair of spring-actuated jaws provided with serrated edges pivoted together, arranged in said socket, lug projecting inwardly from the socket working in grooves in the jaws, and a ring connected to one of the

jaws for adjusting the jaws, for the purpose described.

4. In a device of the kind described, the combination with a handle provided with a 5 tapering socket, of a pair of spring-actuated jaws arranged in said socket, a slot formed in the flattened portion adjacent the handle and

a ring surrounding said portion connected to one of the jaws by a screw passing through the slot, for the purpose described.

CHARLES C. BULL.
